UNITED STATES PATENT OFFICE.

HARDY B. LENTZ, OF SALISBURY, NORTH CAROLINA.

DISPLAY DEVICE.

1,357,879.

Specification of Letters Patent. Patented Nov. 2, 1920.

Application filed March 31, 1919. Serial No. 236,292.

To all whom it may concern:

Be it known that I, HARDY B. LENTZ, a citizen of the United States, residing at Salisbury, in the county of Rowan and State 5 of North Carolina, have invented new and useful Improvements in Display Devices, of which the following is a specification.

This invention relates to means for supporting bedsteads upon the floor of a store 10 for display purposes, the object being to minimize space for supporting the parts in close proximity to each other, and in a manner to permit either part of the bedstead to be swung upon a stationary pivot to a position 15 where it can be thoroughly examined.

In carrying out my invention I provide a combined support and pivot for the bedstead, which embodies a number of interchangeable associated elements of various 20 size, to accommodate different size bedsteads.

The nature and advantages of the invention will be better understood, when the following detailed description is taken in connection with the accompanying drawings, 25 the invention residing in the construction, combination and arrangement of parts as claimed.

In the drawing forming part of this specification like numerals of reference indicate 30 similar parts in the several views and wherein:

Figure 1 is a perspective view showing the manner of supporting the parts of a bedstead in spaced parallel relation in accordance with my invention.

Fig. 2 is a vertical central view through the combined support and pivot.

Fig. 3 is a similar view of a modified form.

Fig. 4 is a similar view of a still further modified form of the invention.

Referring to the drawing in detail, A and B indicate respectively the head and foot of a bedstead arranged in close proximity to each other, and supported for independent movement by the means forming the subject matter of my invention.

This means preferably consists of a socket 10 formed with an annular flange 11 at the base thereof, the latter being provided with the opening 12 through which fastening elements 13 may be passed for attaching or securing the socket upon the floor or other support. Removably positioned within the 55 socket 10, is a tubular member 14 which projects an appreciable distance above the up-

per edge of the socket to fit within the hollow post of either part of the bedstead at one side thereof. Manifestly, in order to associate the parts in this manner one of the 60 casters is removed from one of the posts of the bedstead and the parts then associated in the manner illustrated in Fig. 1. In practice, the sockets 10 are secured upon the floor in pairs as shown in Fig. 1, the socket 65 of each pair being slightly spaced apart. The head and foot members respectively of the bedstead are then arranged parallel in close proximity to each other, and subsequent to the removal of one of the casters 70 from each member of the bedstead, the latter are arranged to receive the tubular members 14. The lower edge of each post receiving one of the tubular members repose upon the upper edge of the socket 10 which 75 of course sustains the weight. In this manner, the parts of the bedstead are arranged to minimize space the invention being particularly designed for use in stores for holding the bedstead in the position as disclosed 80 in Fig. 1 for display purpose. In addition to supporting the bedstead, in the manner shown, the tubular members 14 constitute a fixed pivot about which the parts A and B can be conveniently moved to a position 85 where they can be thoroughly examined.

In Figs. 3 and 4 I show tubular members 15 and 16 respectively, the latter being of relatively different diameters and smaller in diameter than the similar dimension of the 90 tubular member 14. It is of course apparent, that the tubular members 15 and 16 respectively vary in diameter only for a portion of their length, each including enlarged lower end portions 17 of the same diameter 95 to be removably fitted within the socket 10. Consequently, any one of the tubular members 14, 15, and 16 can be operatively associated with the same socket 10, and this interchangeable association permits the invention to be used with bedsteads of different sizes.

While I have shown and described what I consider the preferred embodiment of the invention, I desire to have it understood that 105 the same is merely illustrative; that I do not limit myself to the exact construction disclosed, and that such changes may be resorted to when desired as fall within the scope of what is claimed.

What I claim is:

A bedstead display support comprising in

combination, a hollow annular member adapted to be vertically disposed upon a floor, an annular flange surrounding the lower end of said member and having a plurality of counter-sunk openings for the reception of suitable fastening elements, and a plurality of tubular elements each having a lower portion of the same diameter whereby

said elements are adapted for interchangeable association with the tubular member 10 and the remaining portion of each element varying in diameter from the other elements to accommodate bed-posts of different diameters.

In testimony whereof I affix my signature: 15

HARDY B. LENTZ.
